ADOLF GUND, OF NEW YORK, N. Y.

WALKING TOY.

Application filed September 15, 1923. Serial No. 662,923.

To all whom it may concern:

Be it known that I, ADOLF GUND, a citizen of the United States, and a resident of the city of New York, borough of the Bronx, 5 in the county of Bronx and State of New York, have invented a new and Improved Walking Toy, of which the following is a full, clear, and exact description.

The present invention relates to new and 10 useful improvements in toys, and it pertains more particularly to toys which are adapted to walk in simulation of the animals or other objects which they are constructed to represent.

It is one of the primary objects of the 15 invention to construct a toy in such a manner that as the same is moved over a suitable supporting surface, it will simulate movements of walking.

It is a further object of the invention to 20 construct a toy in such a manner that the movements of walking are carried out automatically without the use of clockworks, springs, or other similar forms of power- 25 supplying mechanism.

With the above and other objects in view, reference is had to the accompanying drawings, in which—

Figure 1 is a longitudinal sectional view 30 of a toy constructed in accordance with the present invention, the sectional view being taken on the line 1—1 of Fig. 3;

Fig. 2 is a longitudinal sectional view of the interior mechanism, the sectional view 35 being taken on the line 2—2 of Fig. 3;

Fig. 3 is a vertical transverse sectional view taken on the line 3—3 of Fig. 1;

Fig. 4 is a view similar to Fig. 3 showing the parts in a different position during the 40 operation of the mechanism.

Referring more specifically to the drawings, the reference character 5 designates the body of a toy, and in the present instance the body is constructed in imitation of a dog or 45 other animal of the quadruped type. The body 5 is preferably filled with suitable stuffing 6, and mounted within the body and surrounded by the stuffing 6, is a channel-shaped frame 7. Mounted upon each side of 50 the channel-shaped frame, at the front end, is a housing 8, and at each side of the rear end of the channel-shaped frame 7, there are two similar housings 9.

Extending into each of the limb extensions 55 of the body, there is a support, and such supports are designated as 10 and 11. The ref-

erence character 10 designates the front supports and the reference character 11 designates the rear supports. As more clearly shown in Fig. 3, the front support 10 on the right-hand side of the body is pivotally connected, as at 12, in the sides of the channel-shaped frame 7, there being a depressed portion 13, said support extending upwardly into the right-hand housing 8. The left-hand support 10 extends upwardly through the left-hand housing 8 and is pivotally mounted in the sides of the channel-shaped frame 7, as at 14, this support having an upwardly bent portion 15. The rear supports 11 are mounted in the same manner as the forward supports, that is, the right rear support is pivotally mounted in the channel-shaped frame as at 16, and has a depressed portion 17 corresponding to the 75 depressed portion 13 of the front support on its respective side, while the left-hand rear support 11 is mounted in the sides of the channel as at 19, and has an upwardly bent portion 20 corresponding to the 80 upwardly bent portion 15 of the forward support on its respective side.

The reference character 21 designates a guide member formed of resilient material and having a centrally disposed portion 22 85 which forms a guide for a flat member 23. This flat member 23 is provided at its forward end with notches 24 and 25 adapted to receive the downwardly bent portion 13 of the right front support and the upwardly 90 bent portion 15 of the left front support, respectively. The rear end of this flat member 23 is provided with notches 26 and 27 adapted to receive the downwardly bent portion 17 of the right rear supporting member 95 and the upwardly bent portion 20 of the left rear supporting member, respectively. This member 23 is adapted to lie in a vertical plane and is carried by the supports 10 and 11, and is maintained in this position by 100 reason of its being received within the centrally disposed portion 22 of the guide member 21.

Attached to the front portion of the toy, there is a string or other suitable device, 30, 105 for pulling the toy along, and it is by this means that the toy is moved over a suitable supporting surface.

By the construction of the supports 10 and 11 and the manner of pivotally connecting them by member 23, the front and rear supports on each side are caused to move simul-

taneously and parallel to one another, so that the toy is canted first to one side and then to the other.

With the parts in the position shown in Fig. 1, the right front support is shown as forward, as is also the right rear support, and the body is canted slightly to the right, as shown in Fig. 3. If, now, the toy be moved forward by means of the string 30, the weight is supported upon the right front support 10 and the right rear support 11 and the body moved forwardly upon the pivotal points 12 and 16 of the supports 10 and 11, respectively. In moving forward from Fig. 3, the body tips or cant to the left, in which position it is shown in Fig. 4, and the weight is transferred from the right-hand supports 10 and 11 to the left-hand supports 10 and 11, and occupies the position shown in Fig. 4. Each time that the weight of the body is transferred from the supports on one side to the supports on the other side and the body moves forwardly, the supports from which the weight is relieved are moved forwardly by the action of the body, this being accomplished through the medium of the reciprocating member 23 and its connection with the supports 10 and 11.

From the foregoing it is apparent that the present invention provides a toy which when moved along a supporting surface will simulate the movements of an animal walking, and that the use of clockworks or other power devices for this purpose, is eliminated.

It is to be understood that the terms "right" and "left" employed in the description of this invention, are used when viewing the toy from the front thereof, rather than pertaining to the right and left sides of the toy.

What is claimed is:

1. In a walking toy, a body, a frame carried by said body, a plurality of supports simulating limbs, said supports being pivotally mounted in the frame and connected in pairs, means for limiting the movement of the supports, a reciprocating member mounted for sliding movement in the frame and pivotally connecting each front support with a rear support on the same side, and means for moving the body along a supporting surface, said reciprocating member serving to cant the body and thereby transfer the weight of the body from one side to the

other to cause a movement of the supports as the body is moved over the supporting surface.

2. In a walking toy, a body, a substantially channel-shaped frame mounted in said body, housings at the front and rear ends of said frame, a pair of supports pivotally mounted in said housings at the front of the body and simulating limbs for the body, a pair of supports pivotally mounted in said housings at the rear of the body and simulating limbs for the body, a centrally disposed reciprocating member slidably mounted in said frame, and means for pivotally connecting the front and rear supports on the same side with the said member, whereby when the toy is moved over a surface it will be canted first to one side and then to the other.

3. In a walking toy, a body, a channel-shaped frame mounted in said body and having a housing at each end, a front support and a rear support mounted in each side of said body and pivotally mounted in said channel shaped frame and working in the housings and being limited in movement by said housings, and a reciprocating member in the frame and pivotally connecting the front and rear supports on each side to operate in unison, whereby as the body is moved along a supporting surface the body will be canted and the weight thereof transferred alternately from the front and rear supports on one side to the front and rear supports on the opposite side to simulate the movements of walking, and means for moving the body along a supporting surface.

4. In a walking toy, a body, a frame mounted within said body, means for moving said body over a suitable supporting surface, a plurality of pivoted supports for said body, there being two on each side thereof, means for limiting the movement of the supports, and means for alternately canting the body to transfer the weight of the body from the supports on one side to those on the opposite side of the body alternately as the body is moved along a supporting surface to simulate the movements of walking, said means comprising a reciprocating member mounted in the frame and pivotally connecting the supports on the same side to operate in unison.

ADOLF GUND.
